US00D976573S

(12) United States Design Patent (10) Patent No.: US D976,573 S
Flygare et al. (45) Date of Patent: * Jan. 31, 2023

(54) MEDICINE CONTAINER

(71) Applicant: Apothecary Products, LLC,
 Burnsville, MN (US)

(72) Inventors: Daniel Bruce Flygare, Chaska, MN
 (US); Daniel Darst, Zimmerman, MN
 (US)

(73) Assignee: Apothecary Products, LLC,
 Burnsville, MN (US)

() Term: 15 Years

(21) Appl. No.: 29/688,898

(22) Filed: Apr. 25, 2019

(51) LOC (14) Cl. 03-01

(52) U.S. Cl.

USPC D3/203.2

(58) Field of Classification Search

FOREIGN PATENT DOCUMENTS

CA 2251234 A1 12/1998

Primary Examiner — Steven J Czyz

(74) Attorney, Agent, or Firm — Merchant & Gould P.C.

(57) CLAIM

The ornamental design for a medicine container, as shown and described.

DESCRIPTION

FIG. 1 is a top perspective view of a medicine container, according to our new design;

FIG. 2 is a bottom perspective view of FIG. 1;

FIG. 3 is a front view of FIG. 1;

FIG. 4 is a rear view of FIG. 1;

FIG. 5 is a left view of FIG. 1;

FIG. 6 is a right view of FIG. 1;

FIG. 7 is a top view of FIG. 1; and,

FIG. 8 is a bottom view of FIG. 1.

1 Claim, 8 Drawing Sheets
